OTTO F. BRUMANN, OF LEYSIN-VILLAGE, SWITZERLAND.

MEANS FOR INTERMIXING FLUIDS.

1,387,832.

Specification of Letters Patent. Patented Aug. 16, 1921.

Application filed September 18, 1919. Serial No. 324,550.

To all whom it may concern:

Be it known that I, OTTO FRANZ BRUMANN, a citizen of the Swiss Confederation, and residing at Leysin-Village, Switzerland, 5 have invented certain new and useful Improvements in Means for Intermixing Fluids, of which the following is a specification.

The present invention has for its object 10 an improved method and means for mixing gases with liquids or for intermixing two or more liquids, especially those of different specific gravity. According to this invention the fluids to be intermixed are conducted 15 into a turbine and are caused to impinge on the rotor blades thereof, which causes the wheel to rotate. The velocity of the turbine may be kept constant, despite fluctuations in the pressure of the fluids, by means of an 20 electrical motor, a transmission gearing or the like, coupled to the turbine shaft.

In order to obtain the maximum mixing effect the turbine is driven at the maximum speed it is capable of attaining, when entirely free of load, under the action of the 25 driving fluid, at which time the external work of the turbine theoretically equals zero, so that all supplied energy is absorbed by the internal work, that is mainly by the mixing 30 work. It will be understood that any given pressure of the driving fluid causes a correlative maximum rotary speed of the turbine, in the sense above defined if, for instance, the useful work of a turbine, used 35 as a motor, amounts to about 60—80% of the available energy, then the losses will respectively amount to about 40—20%; the lower the latter are, the better it is for the desired external dynamic effect.

40 In the present case the situation is reversed since the object to be attained is not an increased output of a motor, but a very thorough commingling of the fluids, in which just that work is utilized which is lost in the motor in the form of friction, power 45 impulses and eddies. According to my invention these losses are intentionally amplified with the result that a relatively large amount of internal work is obtained in the 50 above stated form, which work is then utilized to so break up and scatter the specifically heavier fluid, for instance water, that the respective lighter fluid, for instance gas, can readily invade the heavier fluid and become 55 intimately mixed therewith.

My invention will best be understood

when described in connection with the accompanying drawing in which Figure 1 represents the potential parabola of a turbine; Fig. 2 is a diagrammatic representation of 60 an installation suitable for the purposes of my invention.

In Fig. 1 V denotes the blade velocity, P the useful output, E the available energy, P' the energy parabola, and F the impulse 65 on the blades. The point C then represents the maximum external work of an ordinary turbine when used as prime mover, while the point B represents the minimum external work of the turbine when operating as 70 mixer.

For keeping the operation constant the mixing turbine is coupled directly to an electrical machine or other motor, which is used as a regulator. The rotary speed of this 75 electromotor corresponds to the maximum speed attainable by the turbine, when entirely free of load, under the action of the driving fluid. If less fluid enters the latter its speed will decrease and the electric motor 80 then acts drivingly on the turbine; if more fluid enters, then the motor will act like a dynamo, its current being equalized by the conductors connected to the motor. This regulation has the advantage that a harmful 85 throttling down of the fluids is avoided and that also on relatively low fluid pressure a good mixing action is obtained. The required regulating work is of rather little extent in comparison to the obtained mixing 90 effect.

For enhancing the mixing effect the obtained mixture may be conducted successively to further rotors, which are to be arranged coaxially to the main rotor and which 95 can ride idly on the shaft or are fixed thereto. In the latter instance the fluid passages between blades of one wheel are displaced or staggered relative to those of the adjacent wheel. The mixing device may be arranged 100 vertically or horizontally, and the admission may be radial instead of axial and it may be partial instead of full, without the operation of the installation as described being in any way interfered with.

105 In the construction, diagrammatically shown in Fig. 2, the reference numeral 1 denotes the prime mover, for instance an electromotor, which is coupled to the turbine by the shaft 2. Liquid enters the nozzles 3 110 through the supply pipe 8, while the gas coming in at 9 is conducted to the nozzles 4.

The main turbine wheel 5, the rotor, which is fixed on the shaft 2, carries the blades 7 and, on the fluids issuing from the nozzles 3 and 4 impinging on these blades 7, is caused to 5 rotate in a direction corresponding to that of the electric machine, though the velocities of turbine wheel and electromotor, if left to themselves, may be different. A second 10 blade wheel or rotor 6, arranged loosely on the shaft 2, below the wheel 5 will be taken along by the gyrating mixture impinging on its blades 7' and will thus enhance the mixing 15 effect. The mixture finally is deposited in the bottom part of the turbine drum 10 from where it can be withdrawn at 11.

If a still higher mixing effect is to be obtained the mixture can be reconducted from the drum 10 back again into the turbine 20 through the pipe 12, the turbine on a relatively small lift acting also as pump.

The described method is specially suited for the manufacture of gas-water baths, for instance carbonic acid baths, for making mineral waters, and for many uses in the 25 chemical industries.

What I claim is:—

1. In a device of the character described, a shaft, a turbine wheel thereon to which a driving medium is fed, means for feeding 30 the driving medium to the wheel, whereby the wheel is rotated and the medium is mixed, and means coupled to the turbine to compensate for any change in speed due to the pressure fluctuations in the driving 35 medium.

2. In a device of the character described, a shaft, a plurality of coaxial turbine wheels thereon to which a driving medium is fed, means for feeding the driving medium to

the wheels whereby the energy inhering in 40 the medium as it leaves one of the wheels is utilized for effecting the mixing action in the next wheel, and means coupled to the turbine to compensate for any change in speed of the turbine due to the pressure fluctuations in 45 the driving medium.

3. In a device of the character described, a shaft, a plurality of coaxial turbine wheels thereon to which the driving medium is successively fed, means for feeding the driving 50 medium to the wheels whereby the energy which still inheres in the medium as it leaves one of the wheels is utilized for effecting the mixing action in the next wheel, an electric machine coupled to the turbine, means whereby the speed of the electric machine is kept equal to that of the turbine under normal working pressure of the driving medium, whereby said electric machine will compensate for any change in speed of the 60 turbine due to pressure fluctuations in the driving medium.

4. In a device of the character described, a shaft, a plurality of coaxial turbine wheels thereon to which a driving medium is successively fed, means for feeding the driving 65 medium to the wheels whereby the energy still inhering in the medium as it leaves one of the wheels is utilized for effecting a mixing action in the next wheel, a motor coupled 70 to the turbine and means whereby the speed of the motor is kept equal to that of the turbine under normal working pressure of the driving medium, whereby said motor will compensate for any change in speed of the 75 turbine due to pressure fluctuations in the driving medium.

OTTO F. BRUMANN.
